J. C. LANG.
Floating Fire-Engines.

No. 135,922.

Patented Feb. 18, 1873.

UNITED STATES PATENT OFFICE.

JOHN C. LANG, OF WASHINGTON, DISTRICT OF COLUMBIA, ASSIGNOR OF
THREE-FOURTHS HIS RIGHT TO PHILLIP B. FOUCHE, OF NEW ORLEANS,
LOUISIANA.

IMPROVEMENT IN FLOATING FIRE-ENGINES.

Specification forming part of Letters Patent No. 135,922, dated February 18, 1873.

To all whom it may concern:

Be it known that I, J. C. LANG, of Washington city, District of Columbia, have invented certain Improvements in Vessels known as Floating Fire-Engines, of which the following is a specification:

My invention relates to the construction of a pivoted gangway to project from the bow of any boat used for the purposes of a fire-engine and to reach the decks of a burning vessel without materially endangering the boat, of which the gangway is a part, though said boat may not be constructed of fire-proof materials. For this purpose the gangway is made of iron, lightly and strongly built with a view to resist any lateral or downward strain. It is fitted at its outward end with a hook or hooks for the purpose of laying hold of and drawing from the moorings either a burning vessel or one the safety of which may be endangered by the too close proximity of burning or inflammable matter.

By reference to the drawing, which is a part of this specification, it will be seen that Figure 1 represents a side elevation of a boat embodying my invention. Fig. 2 is a plan of the same. Fig. 3 is an elevation on line xx enlarged, showing gearing for giving motion to the gangway.

The gangway AA is pivoted at PP near its center, and may be moved vertically through an arc of fifteen or twenty degrees. It is put in motion by turning the capstan C , upon the cylinder of which is fitted a helical

fillet interlocking with spur-wheel B upon shaft b , thereby communicating rotary motion to spur-wheels e , which interlock with cogged segment fff of the gangway. The chains gg and hh , Fig. 1, also assist in giving motion to the gangway by being wound on or off the capstan-cylinder at ii , Fig. 3. Upon the main deck of the boat amidships, or at any convenient point, is placed one or more force-pumps, from which pass the metallic pipes MM , Fig. 2, said pipes passing along or within the gangway to the pivot-point P , where they connect, by a movable joint, J , with a pipe, N , which ends with the discharge-nozzle oo near the forward end of the gangway.

I make no claim to the appliances for giving motion to the gangway, believing them both to be well-known mechanical movements; nor do I claim as new the hook or hooks which is placed at the forward end of the gangway.

Claim.

What I do claim as new, and desire to secure by Letters Patent, is—

The combination and arrangement within a gangway or movable platform, of the pipe or pipes, substantially as described, adapted to be used in connection with suitable force-pumps, for the purposes set forth.

JOHN C. LANG.
